HAIR NET

George A. Saigh, Brooklyn, N. Y.

Application October 22, 1940, Serial No. 362,247

2 Claims. (Cl. 132—49)

This invention relates generally to women's hair nets, but more specifically to a hair net which serves the purpose of a turban, of a beauty aid cap and of a triangular veil net.

The main object of the invention resides in the provision of a hair net which remains in place when applied to the head regardless of the movement of the latter. This is accomplished by means of a continuous elastic band running through the length of both the upper edge of 10 the net and of the continuous side members, the latter being adapted to be crossed in the rear whereby the ends are brought up to the middle portion of the forehead and there adapted to be secured to the body portion of the net. By such 15 construction, a hair net is provided which is applied and serves as a turban, the latter being wearable in the street during the day as well as during the night.

A further object of the invention resides in the provision of a hair net which is reinforced along the mid portion of the cap member whereby the side members at the point of junction are prevented from tearing during application 20 and removal.

A further object of the invention resides in the provision of a hair net which keeps the coiffure of the wearer in excellent shape.

These objects and other incidental ends and 30 advantages of the invention will hereinafter appear in the progress of the disclosure and as pointed out in the appended claims.

Accompanying this specification is a drawing showing a preferred form of the invention wherein corresponding reference characters designate corresponding parts through the several views and wherein:

Figure 1 is a rear view of the hair net as applied to a woman's coiffure.

Figure 2 is a side view thereof.

Figure 3 is a front view of the net as applied to a woman's coiffure.

Figure 4 is a plan view of the upper surface of the hair net in flattened and outstretched position.

In accordance with the invention the hair net consists of two similar triangular shaped portions generally designated by numerals 10 and 11 secured together at opposite edges by a strong and appropriate line of stitching 12. Portions 10 and 11 are made of strands of hair, silk or other suitable material knitted together to form meshes. An elastic band 13 is secured along the upper edge of the hair net and terminates at the lower ends in the form of elastic loops 14, the

formation of the said loops being accompanied by gathering 14a of the net material adjacent thereto. At the mid portion of the elastic edge and along the upper end of stitching 12, the net material is gathered as at 15 by means of appropriate stitching which secures button 16 at the meeting point of elastic edges 13. The lower edges of portions 10 and 11 are provided with a reinforcing strand 17.

Stitching 12 offers reinforcement to the net especially at the junction of the lower edges of triangular portions 10 and 11. These portions 10 and 11 form a central body or cap 18 and band members 19, 19. Cap 18 by the use of gatherings 14a, 14a and 15 assumes a dome shape to cover the coiffure while bands 19, 19 serve the function of both tightening members for the cap and of giving the net a turban effect. For in applying the net to the hair, the net is placed over the top of the head so that button 16 is in front and the band members 19, 19 are hanging in the back. The ends of band members 19, 19 are grasped and crossed from behind thereby tightening the net over the hair. Thereafter, the said ends are brought forward and the loops 14, 14 are secured to button 16. Where the net is not to be applied to the hair, it may be used as a triangular veil.

It has been found that by the present construction, a sturdy hair net is formed which cannot roll over the top of the head, the tightness of fit being determined by the amount of tension used in crossing bands 19, 19 at the rear of the head.

I wish it understood that minor changes and variations in the shape, construction, material and location of parts, may all be resorted to without departing from the spirit of the invention and without departing from the scope of the appended claims.

I claim:

1. A hair net of interwoven strands comprising two similar and opposite triangular members, stitching means joining corresponding sides of the triangular members to form a triangular shaped body having inclined elastic lateral edges meeting at the top, the said inclined elastic lateral edges being adapted to obliquely engage the periphery of the head of the wearer, and opposite and upwardly inclined reinforced lower edges meeting at the lower end of the stitching means, the free lower ends of the triangular members serving as band members and being adapted to be crossed rearwardly of the head of the wearer to be brought forward

over the head, means of securing the free ends of the triangular members to the juncture of the elastic lateral edges after said free ends are crossed rearwardly and brought forward over the head of the wearer.

2. A hair net of interwoven strands comprising two similar and opposite triangular members, stitching means joining corresponding sides of the triangular members to form a triangular shaped body having inclined elastic lateral edges meeting at the top, the said inclined elastic lateral edges being adapted to obliquely engage the periphery of the head of the wearer, and opposite and upwardly inclined reinforced lower

edges meeting at the lower end of the stitching means, the free lower ends of the triangular members serving as band members and being adapted to be crossed rearwardly of the head 5 of the wearer to be brought forward over the head, means of securing the free ends of the triangular members to the juncture of the elastic lateral edges after said free ends are crossed rearwardly and brought forward over the head of the wearer, and means to shape the triangular body near the juncture of the lateral edges to the form of the head of the wearer.

GEORGE A. SAIGH.
